Patented February 9, 1904.

UNITED STATES PATENT OFFICE.

MAURICE BLUM, OF LA CHAUX-DE-FONDS, SWITZERLAND.

WATCH-BARREL.

SPECIFICATION forming part of Letters Patent No. 751,896, dated February 9, 1904.

Application filed October 2, 1903. Serial No. 175,507. (No model.)

To all whom it may concern:

Be it known that I, MAURICE BLUM, a citizen of the Republic of Switzerland, and a resident of La Chaux-de-Fonds, Switzerland, have 5 invented a new Watch-Barrel, of which the following is a specification.

The accompanying drawings, furnished as an example, represent a form of the present invention, Figure 1 being a plan, and Fig. 2 a 10 section, on a larger scale, taken through $\alpha\alpha$, Fig. 1, the barrel being shown in place on a watch-movement.

This kind of barrel has been studied in order to produce a watch-movement as reduced 15 in height as possible, while keeping the barrel of sufficient height. This result is obtained by dispensing with the barrel-bridge, its arbor A being fixed only in the main plate P of the movement. In order to render the 20 arbor A sufficiently rigid, its lower end is first perfectly fitted at e in the plate P, then fitted square in the ratchet R, and firmly held by a screw V. When this screw is tightly screwed up, the ratchet R, which is sunk in a corre-

sponding recess p , formed under the plate P, 25 rests against a circular edge r on the bottom of this recess, whereby great stability for the arbor A is insured without undue friction.

A barrel of this kind, the dimensions of which may vary, can be applied to any kind 30 of watch.

Having now described my invention, I claim as new and wish to secure by Letters Patent—

In combination with a watch, a main plate having a recess formed on its under face, a 35 circular edge r on the bottom of said recess, a ratchet-wheel fitting in said recess and resting on said edge r a watch-barrel, and an arbor and screw securing the barrel and ratchet-wheel to the main plate, substantially as de- 40 scribed.

In witness whereof I have hereunto set my hand in presence of two witnesses.

MAURICE BLUM.
